UNITED STATES PATENT OFFICE.

GEORGE B. HEATH, OF ST. LOUIS, MISSOURI.

REFLECTOR.

Application filed July 31, 1925. Serial No. 47,344.

This invention relates generally to street-lighting systems and, more particularly, to a certain new and useful improvement in light reflectors especially adapted for use in such systems.

Present day street lighting systems in which the lamp-posts or standards are located along the street-curb, have been found largely objectionable, particularly in residence sections, so far as I am aware, in that the rays of light projected in all directions from the source disturb the privacy of abutting householders. My present invention has hence for its chief object the provision of means in the form of a reflector so shaped and constructed as to for the most part reflect the projected rays of light outwardly towards the street and thus away from, and thereby obviate disturbance or annoyance of, abutting householders and yet at the same time permit some of the projected rays of light to filter through to sufficiently illuminate the adjacent side-walk.

And with such object in view, my invention resides in the novel features of form, construction, arrangement, and combination of parts hereinafter described and pointed out in the claims.

Referring now by reference characters to the accompanying drawing, which illustrates a street-lamp embodying a preferred form of reflector embodying my invention, A designates a globe of glass or other suitable transparent or translucent material and of suitable form and design, topped with a suitable metal or glass cap B and adapted for support, as is common, on a post or standard, not shown. Suitably disposed within globe A and adapted for inclusion in an electric circuit, is a bulb C or other source of light-rays.

Depending within globe A, is an arm D, supported by which within globe A in suitably centered relation to bulb or other source of light C, is a reflector E of my invention. This reflector E is constructed of any suitable preferably metallic material and has preferably a polished convexed inner surface of spherical, parabolic, or other suitable curvature. A reflector of solid or rather imperforate material would reflect all the rays of light emanating from bulb C and cast a solid black or densely dark shadow. However, the present reflector E is formed or provided with a multiplicity of orifices, perforations, or other small apertures or

openings F, which construction, I have found, reflects the bright rays of light of bulb C outwardly towards the street and yet permits some of the projected rays to filter through to sufficiently illuminate the adjacent pavement, the shadow cast by the reflector to its rear being indicated approximately by the dot and dash line of the drawing and being soft or mellow. Thus in a simple and inexpensive manner, I effectively remove the present stated objection to street lighting systems of the type mentioned, without, however, affecting the efficiency of the globes A in sufficiently lighting the street and sidewalk.

It will be understood, of course, that a shifting of the reflector E relatively to the source of light C will vary the line of shadow, that the finer the perforations or openings E the denser the cast shadow, and that minor changes in the form, construction, arrangement, and combination of the several parts of the reflector may be made and substituted for those herein shown and described without departing from the nature and principle of my invention.

Having thus described my invention, what I claim and desire to secure by Letters Patent is:

1. In a street lamp, an enclosing globe, a source of light within the globe, and a reflector disposed within the globe and in centered rearward relation to the source of light, the reflector comprising a body of suitable curvature for reflecting the light-rays outwardly towards the street, said body being provided with a multiplicity of perforations for permitting some of the light-rays to filter rearwardly therethrough for illuminating the adjacent pavement.

2. In a street lamp, an enclosing globe, a source of light within the globe, an arm disposed within the globe, and a reflector supported by said arm within the globe and in centered rearward relation to the source of light, the reflector comprising a body having a convexed surface for reflecting the light-rays outwardly towards the street, said body being provided with a multiplicity of perforations for permitting some of the light-rays to filter rearwardly therethrough for illuminating the adjacent pavement.

In testimony whereof, I have signed my name to this specification.

GEORGE B. HEATH.
